Patented Jan. 22, 1974

230,101

CARRYING CASE FOR CASSETTES

Morris L. Green, 239 Paramount Ave.,
Salt Lake City, Utah 84115

Filed May 10, 1971, Ser. No. 142,119

Term of patent 14 years

Int. Cl. D3—99

U.S. Cl. D87—1

FIG 1

FIG. 1 is a front perspective view of a carrying case for cassettes showing my new design, the end not shown being a mirror image of the end shown;

FIG. 2, a top plan view, with the cover open, drawn to a reduced scale;

FIG. 3, a front elevation view, drawn to the same scale as FIG. 2;

FIG. 4, an end elevation view; and

FIG. 5, a rear elevation view.

I claim:

The ornamental design for a carrying case for cassettes, substantially as shown and described.
